UNITED STATES PATENT OFFICE.

GEORGE O. JORDAN, OF NORTH ATTLEBORO, MASSACHUSETTS, ASSIGNOR TO JAMES R. FEELEY CO. INC., OF PROVIDENCE, RHODE ISLAND, A CORPORATION OF RHODE ISLAND.

DESIGN FOR A MEDAL.

Application filed January 23, 1926. Serial No. 16,233. Term of patent 3½ years.

To all whom it may concern:

Be it known that I, GEORGE O. JORDAN, a citizen of the United States of America, residing at North Attleboro, county of Bristol, State of Massachusetts, have invented a new, original, and ornamental Design for a Medal, of which the following is a specification, reference being had to the accompanying drawing, forming a part thereof.

I claim:

The ornamental design for a medal, substantially as shown.

GEORGE O. JORDAN.
